UNITED STATES PATENT OFFICE

144,636

DESIGN FOR AN ELECTRIC LIGHT BULB

Norbert Shaeffer, Hollywood, Calif., assignor to
Universal Microphone Co., Inglewood, Calif., a
partnership

Application September 25, 1945, Serial No. 122,343

Term of patent 7 years

(Cl. D26—8)

To all whom it may concern:

Be it known that I, Norbert Shaeffer, a citizen of the United States, residing at Hollywood, in the county of Los Angeles and State of California, have invented a new, original, and ornamental Design for Electric Light Bulb, of which the following is a specification, reference being had to the accompanying drawing, forming a part thereof, wherein:

Fig. 1 is a side view of an electric light bulb embodying my new design;

Fig. 2 is a top end view;

Fig. 3 is a bottom end view; and

Fig. 4 is a perspective view.

I claim:

The ornamental design for an electric light bulb, substantially as shown.

NORBERT SHAEFFER.
